UNITED STATES PATENT OFFICE.

ADOLPH CLAUS, OF LOWELL, MASSACHUSETTS, ASSIGNOR OF ONE-HALF
TO JOSEPH S. LUDLAM, OF SAME PLACE.

SHEDDING MECHANISM FOR LOOMS.

SPECIFICATION forming part of Letters Patent No. 243,361, dated June 28, 1881.

Application filed January 8, 1881. (No model.)

To all whom it may concern:

Be it known that I, ADOLPH CLAUS, of Lowell, county of Middlesex, State of Massachusetts, have invented a new and useful Improvement in Sheding Mechanisms for Looms, of which the following description, in connection with the accompanying drawings, is a specification.

This invention relates to that class of shedding mechanisms for looms known among weavers as "dobbies," and is an improvement on United States Patent No. 217,589, July 15, 1879, to which reference may be had. The devices or parts in this application common to the said patent are designated by like letters herein. In that patent the hooked jacks are raised and lowered, to place them in contact with the lifters, through the intervention of rods provided each with two collars, the said rods being extended through guide-bars, which direct their movement, each rod being extended through horizontal slots in two of the said jacks on one connector, a single finger on a pattern-chain operating a single rod, the latter by its two collars controlling the rising and falling motions of the two jacks, through which it is extended.

In the loom referred to, when the hooked jacks and their pivoted connectors have to be removed, as is frequently necessary, on account of the breaking of a jack or bending of parts, the cross-bars above the said hooked jacks have first to be removed, and also the rod controlling them, before the jacks can be taken from the loom, this requiring very considerable time. It has been my object to so improve the said loom that the jacks may be instantly removed whenever desired, and so that each jack of the upper and lower series may be operated directly by its own finger.

Figure 1 represents, in side elevation, the devices employed in the patented loom referred to for operating the lifters and pattern. Fig. 2 is a sectional detail, showing the heddle-levers, notched jacks, and my improved devices for raising and lowering them at the proper times, in order that they may be engaged by one of the lifters. Fig. 3 is a right-hand end view of Fig. 1, partly in section, the pattern-chain, heddle-levers, and jacks shown in Fig. 2 being added. Fig. 4 represents one of my finger-con-

necting rods attached to the fingers, but removed from the machine; and Fig. 5 is a side view of one of the said rods.

A pinion, j^5 , supposed to be at the end of the usual crank-shaft of the loom, engages the pinion k^5 , having a crank-pin, o^5 , joined by the rod p^5 with an arm of one of the levers r^5 on shaft x , the said levers having links w^5 w^5 , connected with the lifters s^5 t^5 , adapted to slide in the slots x^5 as the said levers r^5 are vibrated, the said lifters engaging the notched jacks d^6 or c^6 , according to which one of the said jacks is lowered into a position to be caught by the said lifters.

The heddle-levers x^4 are joined, as usual, by cords w^4 , with the upper portions of the harness-frames. (Not shown.) These heddle-levers x^4 have slotted bearing portions 17, to receive the fulcrum-pins 17*, located at the centers of the jack-connectors f^6 , to the lower and upper ends 70 of which the jacks d^6 c^6 are pivoted.

The shaft, upon which is secured the gear k^5 , before referred to, has at its other end the bevel-gear l^5 , which engages the bevel-gear m^5 on a short vertical shaft, having at its top a worm-gear, n^5 , which engages a worm-toothed pinion, e^5 , fully described in the said patent, it being placed upon the shaft c^5 , (see Fig. 3,) fully described in the said patent, the said gear being instrumental in giving motion to the pattern chain or surface d^5 , composed of bars 26 and suitable pins thereon. The notched jacks in the said patent are slotted for the passage through them of the rods, on which are placed the projections or washers which lift the said jacks. A cross-bar of the said patent, directly above the jacks d^6 , (see Fig. 8 of the drawings pertaining thereto,) prevents the said jacks from being lifted from the upper ends of the rods b^6 therein shown; and to remove the said jacks it 90 becomes necessary to first take away the said cross-bar and then remove a similar cross-bar from above the lower series of jacks, c^6 , after which the jacks d^6 may be turned upward from the ends of the said rods b^6 ; but the rods cannot be removed until the front side or cap part (not therein shown as removable) is removed from the guide, (shown in section as located below the hooked jacks d^6 ,) in which the rods b^6 slide vertically, and then the hooked jacks 100

and their connector f and rod may be freely removed from the loom.

In this my improved loom the jacks are lifted by a series of weighted fingers, $a^7 b^7$, pivoted at $a^8 b^8$, each finger having a toe, a^{12} or b^{12} , at its inner end to bear against the curved under side of and keep the jacks $c^6 d^6$ elevated out of range of the lifters s^5 and t^5 , which are moved simultaneously in opposite directions. The jacks are lifted whenever a finger, a^7 , is permitted to fall into its lowermost position (see Fig. 2) by the absence from under it of a pin of the pattern-chain d^5 . The outer ends of these weighted fingers $a^7 b^7$ are joined by adjustable wire links $c^7 c^8$, each one having near its center a loop, c^8 , which may be pinched or closed more or less, as may be desired, to provide for wear of the parts and to insure accurate adjustment and position with relation to each other and the pattern-chain of the fingers $a^7 b^7$.

In this my improved loom the jacks $c^6 d^6$ are not slotted, and are consequently made much thinner and stronger than were they slotted, and, besides being more cheaply made, are less liable to be broken or injured in use.

When for any purpose it is desired to remove from the loom a connector, f^6 , and its attached jacks $d^6 c^6$, it is only necessary to lift the pivots of the connectors from the slotted portions 30 of the heddle-levers x^4 and elevate them out of the machine, the hooked jacks d^6 being free to readily pass underneath the cross-bar d^7 above them.

Some of the parts shown in the drawings being not of my invention, and being fully shown in the patents hereinbefore referred to, I have deemed it unnecessary to fully describe their operation, notwithstanding I have placed upon or near them letters of reference common to the 40 said patent.

By the employment of the fingers $a^7 b^7$, one for each jack, and connecting the outer ends of the fingers by means of the adjusting devices or wires c^7 , I am enabled to move the said fingers in unison together in the same direction, 45 and consequently with them the hooked jacks $c^6 d^6$, thus enabling me to do away with the rods b^6 and their washers 15 and 16, (shown in the said patent,) and also avoid the making of slots in the said jacks, which, in my opinion, 50 weaken the said jacks.

I claim—

1. The heddle-levers x^4 , the series of connectors f^6 and their attached hooked jacks $c^6 d^6$, lifters $s^5 t^5$, and means to move the said lifters, combined with the two independent series of fingers $a^7 b^7$, one finger for each jack, the wires or connectors c^7 between the said fingers, the pattern chain or surface, and means to move it, substantially as and for the purpose 60 described.

2. The two series of weighted fingers $a^7 b^7$, their connecting-rods c^7 , provided with loops c^8 , the pattern-cylinder, and means to move it and actuate the said fingers in unison, combined with the hooked jacks operated upon directly by the said fingers, the connectors between the hooked jacks, the lifters, and means to reciprocate them to engage any of the jacks which may be permitted to fall within their 70 range of movement, substantially as and for the purpose described.

In testimony whereof I have signed my name to this specification in the presence of two subscribing witnesses.

ADOLPH CLAUS.
